UNITED STATES PATENT OFFICE.

EUGENE F. BRADY, OF ALTOONA, PENNSYLVANIA.

ROUNDHOUSE.

SPECIFICATION forming part of Letters Patent No. 677,929, dated July 9, 1901.

Application filed April 30, 1901. Serial No. 58,125. (No model.)

To all whom it may concern:

Be it known that I, EUGENE F. BRADY, a citizen of the United States of America, residing in the city of Altoona, in the county of Blair, 5 in the State of Pennsylvania, have invented a certain new and useful Improvement in Roundhouses, of which the following is a true and exact description, reference being had to the accompanying drawings, which form a 10 part thereof.

My invention relates to the construction of locomotive-roundhouses, and has for its object, primarily, to provide for an improved construction and combination of the roundhouse with trolley-supported doors for opening and closing the passages by which the 15 engines enter and leave the roundhouse.

A further object of my invention is to provide a convenient construction for increasing 20 the size of roundhouses which are too small to receive the modern long locomotive.

The nature of my improvements will be best understood as described in connection 25 with the drawings in which they are illustrated, and in which—

Figure 1 is a front elevation showing my system of suspended doors. Fig. 2 is a cross-sectional view taken as on the section-line 2 2 of Fig. 1. Fig. 3 is a plan view of the 30 roundhouse on a smaller scale; Fig. 4, an enlarged view similar to that shown in Fig. 2, showing in detail the track and trolley arrangement; and Fig. 5 is a plan view showing a section of the trolley-tracks with trolleys in place thereon.

A indicates the roundhouse, of ordinary construction; B', B², B³, B⁴, and B⁵, tracks radially arranged in the roundhouse; B⁶ and B⁷, sections of track terminating in a turn-table 35 pit, and B⁸ and B⁹ the turn-table working in said pit, adapted to register with each of the roundhouse-tracks.

C C, &c., are the columns forming the front 40 wall of the roundhouse proper.

C' and C² are beams secured to the columns and forming an outwardly-extending bracket, as shown, the upper member C' of the bracket supporting an extension-roof, (indicated at C³) and C⁴ indicating a downwardly-extending 45 plate secured on the outer ends of the brackets, as best shown in Fig. 4.

D is a downwardly-extending plate also se-

cured to the outer ends of the brackets, one such plate extending over each two successive pairs of tracks, and each said plate supporting at its lower end the two parallel trolley-tracks, (indicated at D' and D²), said tracks also extending over each successive pair of railway-tracks.

E (see Figs. 1 and 2) is a guideway situated immediately below the trolley-tracks and between the pair of railway-tracks over which the trolley-tracks extend.

F and F' are doors, the lower ends of which are held together and in proper place by engagement with the guideway E and which are supported from above on trolleys running on the tracks D' and D². As shown, each door is provided with a hanger, as indicated at F², the upper ends of the hangers being turned over and downward, as indicated at F³, so as to form supports for the pivot-pins F⁴ upon which the trolleys F⁵ are journaled, said trolleys resting in turn upon the tracks D' and D².

F⁶ and f⁶ indicate the handles by which the doors F and F' are moved.

It will be obvious that by the construction above described the doors F and F' can be made to extend over and close the doorways through which the pair of tracks B and B', for instance, extend; also, that by sliding the outer door F' in front of the door F the track B is opened, while by moving the door F behind the door F' the track B' is opened. It is also obvious that my door system may be combined with any construction of roundhouse; but I have found it especially convenient in cases where the tracks within the roundhouse are too short for modern locomotives and in which a front extension to the houses is desirable, such extension being provided for by the brackets C' C², supporting the extension-roof and also supporting the trolley-tracks for the sliding doors.

Having now described my invention, what I claim as new, and desire to secure by Letters Patent, is—

1. A locomotive-roundhouse having radially-arranged tracks, and doorways through which successive pairs of such tracks extend, in combination with double overhead-trolley tracks D' D² extending over each such doorway and pair of tracks and a pair of suspend-

ed doors F and F' having trolleys resting on said tracks, one each adapted to close one half the doorway so that the doorway may be entirely closed or either half thereof opened by shifting the doors on the tracks.

2. A locomotive-roundhouse having radially-arranged tracks, and doorways through which successive pairs of such tracks extend, in combination with double overhead-trolley tracks D' D² extending over each such doorway and pair of tracks, a pair of suspended doors F and F' having trolleys resting on said tracks one each adapted to close one half the doorway so that the doorway may be entirely closed or either half thereof opened by shifting the doors on the tracks, and a stationary guideway E secured between the tracks at the bottom of the doorway for holding the bottoms of the doors together and in place.

3. A locomotive-roundhouse having radially-arranged tracks and a series of columns C forming the front wall of the roundhouse proper and between which the tracks issue, in combination with brackets C' C² extending out from the columns C, and supporting an extension-roof C³, overhead-trolley tracks D' D² supported on the brackets and arranged in pairs to extend over successive pairs of railway-tracks and suspended doors F F' supported on trolleys from the tracks D' D² and adapted to extend over either or both of the pair of railway-tracks lying beneath each pair of trolley-tracks.

EUGENE F. BRADY.
